UNITED STATES PATENT OFFICE.

MARK W. DEWEY, OF SYRACUSE, NEW YORK.

DESIGN FOR AN ELECTRIC-HEATER CASING.

SPECIFICATION forming part of Design No. 22,017, dated November 22, 1892.

Application filed October 19, 1892. Serial No. 449,404. Term of patent 14 years.

To all whom it may concern:

Be it known that I, MARK W. DEWEY, a citizen of the United States, residing at Syracuse, in the county of Onondaga and State of New York, have invented and produced a new and original Design for an Electric-Heater Casing, of which the following is a specification, reference being had to the accompanying drawings, forming part thereof.

In said drawings, Figure 1 shows a perspective view of an electric-heater casing embodying my design, and Fig. 2 is a vertical transverse section of the same.

The leading feature of my design consists in the case C, presenting at opposite sides

two broad surfaces, which have their marginal portions *o o* meeting at their edges. Said case is perforated or formed with openings *c c* in the upper and lower portions of its sides and top and bottom walls, as shown. 20

What I claim is—

The design for an electric-heater casing, substantially as shown and described.

In testimony whereof I have hereunto signed my name this 17th day of October, 1892.

MARK W. DEWEY.

Witnesses:

H. M. SEAMANS,
C. L. BENDIXON.
